UNITED STATES PATENT OFFICE

HERMAN G. POSSNER, OF MESHANTICUT PARK, RHODE ISLAND.

FASTENER.

Application filed June 19, 1924. Serial No. 720,980.

To all whom it may concern:

Be it known that I, HERMAN G. POSSNER, a citizen of the United States, residing at Meshanticut Park, in the county of Providence and State of Rhode Island, have invented certain new and useful Improvements in Fasteners, of which the following is a specification.

This invention relates to bendable garment fasteners of the class adapted more particularly to be used by laundries as temporary fasteners for soft cuffs and neck bands of freshly laundered shirts and other articles of clothing; and the invention has 10 for its object to form such a fastener of a thin strip of readily bendable metal which is embossed or otherwise stiffened or strengthened along its length leaving a portion of less strength than the stiffened portions, whereby the fastener after having been positioned in a garment may be folded by applying pressure to the ends of the strip causing them to grip and bind the several layers of fabric together.

25 With these and other objects in view, the invention consists of certain novel features of construction, as will be more fully described, and particularly pointed out in the appended claims.

30 In the accompanying drawings:

Figure 1 is a perspective view of a soft cuff freshly laundered, and showing the parts as held in position by one form of my improved bendable fastener which is 35 shown in full lines and also illustrating another form of my improved fastener in dotted lines positioned in the buttonholes of a cuff.

Figure 2 is a view of one form of my improved fastener as binding together the parts of the neck band of a shirt.

Figure 3 is a top view showing one form of my improved metal fastener in extended position.

45 Figure 4 is a sectional edge view of the fastener illustrating the stiffening ribs arranged along its length to leave the unstiffened portions between the ends of the ribs where the strip will bend when a folding pressure is exerted on its ends.

Figure 5 is a perspective view showing the strip in folded position.

Figure 6 is a modification showing another form of my improved bendable fastener strip extended.

Figure 7 shows the strip illustrated in Figure 6 as in folded position. It is found by laundries where bendable metal members are applied to the buttonholes of freshly laundered soft cuffs and the like, that unless a stiffened bridge portion is provided in the metal strip, of a length substantially the thickness of the multiple layers of soft fabric of the cuff that it is difficult to cause the fastener to lie properly and to make its ends grip and hold the parts of the cuff fabric as it should, and to obviate this difficulty, I have provided a strip of metal of the proper size and embossed the same with one or more stiffening ribs forming a stiffened bridge portion with two stiffening arms the ribs being arranged with a space between their ends whereby a folding pressure on the ends of the arms causes them to bend in the space between the ribs leaving a stiffened bridge portion of the desired length to extend through the buttonholes of the cuff and permit the arm portions to lie flat against the opposite faces of the cuff fabric to grip and bind it in position, and the following is a detailed description of one construction of fastener by which these advantageous results may be obtained:

With reference to the drawing, 10 designates a strip of metal of the desired length which is preferably formed very thin and of a ductile, soft or bendable quality, the same being adapted more particularly to be passed through buttonholes of freshly laundered soft cuffs and the like, for the purpose of holding the several layers of fabric in the desired finished position.

It is found in practice of advantage to so form this fastener that it shall have a 95 stiffened middle or bridge portion 11 having a length substantially the thickness of the several layers of cuff fabric so that its lines of bending will be at the ends 13 of the bridge portion 11 which will permit the 100 arm portions 12 at either end of the bridge to be folded downwardly against the cuff fabric to bind the same permanently in position.

To accomplish this in one simple and effective way, as shown in Figures 3, 4 and 5, I have stiffened arm portions 12 and also stiffened bridge portions 11 by ribs 14 and 15 respectively, leaving unribbed portions at the ends of the bridge as at 13, whereby 110

when a folding pressure is applied to the ends of the arm portions of the strip it naturally bends along its unsupported lines which will be at the points 13 and when bent into the desired shape in folded position against the sides of the cuff fabric it will grip and bind these fabric portions firmly in position.

In some instances instead of making the strip of the same width throughout its length, as illustrated in Figure 3, I sometimes reduce the width of the strip at its bridge portion 17, see Figures 6 and 7, and I rib this bridge portion as at 18 to stiffen the same leaving an unribbed portion at the ends of the bridge where the arms or enlarged head portions 16 will bend to be folded against the sides of the cuff portions or fabric.

It will be noted in the construction shown in Figures 6 and 7 that the enlarging of the stock of the arms over the width of the bridge stock, stiffens the arm portions of the device similarly to the ribs 14 in the strip member illustrated in Figure 3, whereby a folding pressure on the ends 16 will cause the bridge portion to bend at its ends 19.

It will be noted that by the use of my improved foldable fastener, it is only necessary to pass one end of the metal strip through the buttonholes of the fabric and then by drawing the thumb and finger endways with a wiping or stripping motion the arms or ends of the metal strip are readily bent down and caused to lie against the opposite faces of the fabric.

By forming a narrow bridge portion as illustrated in Figure 6, the same may be after having been passed through the buttonholes of the cuff, turned around into position illustrated in full lines in Figure 1, if desired, or when the strip with the wider bridge portion illustrated in Figure 3, is passed through the buttonholes 20 of the cuff they will naturally lie in position illus-

trated in dotted lines in this said Figure 1.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A cuff fastener formed of a thin strip of bendable metal having arm portions connected by a bridge portion, and an embossed stiffening rib on said bridge portion terminating short of said arm portions to provide a bendable portion between said arm and bridge portions.

2. A fastener formed of a thin strip of readily bendable metal embossed longitudinally at intervals along its length forming stiffening ribs thereon spaced apart at their ends, whereby the fastener is adapted to bend at its unribbed internal portions when a folding pressure is applied to its end portions.

3. A fastener formed of a strip of bendable metal, different longitudinally disposed embossed stiffening ribs thereon having their ends spaced apart leaving an unembossed transverse portion, whereby a folding pressure upon the ends of the strip will cause the same to first bend at the unembossed portions.

4. A cuff fastener formed of a thin strip of readily bendable metal having two arm portions connected by a bridge portion, said arms and bridge portions having stiffening embossed ribs, the ribs in the different portions being spaced apart at their ends whereby said strip will bend between the ends of said arm ribs and bridge rib when a folding pressure is applied to said arm portions.

In testimony whereof I affix my signature.

HERMAN G. POSSNER.
